(57) **CLAIM**

The ornamental design for a holder for a handset, as shown and described.

DESCRIPTION

FIG. 1 is a front view of a holder for a handset showing our new design;

FIG. 2 is a bottom plan view thereof;

FIG. 3 is a perspective front view thereof;

FIG. 4 is a perspective rear view thereof;

FIG. 5 is a right side view thereof;

FIG. 6 is a left side view thereof; and,

FIG. 7 is a rear view thereof.

The broken line showing various regions are for illustrative purposes only and form no part of the claimed design. The unshown portions form no part of the claimed design.
